UNITED STATES PATENT OFFICE.

FRANK L. THOMPSON, OF WHEATLAND, OKLAHOMA TERRITORY.

TAIL-BLOCK FOR SULKY-PLOWS.

No. 860,704.

Specification of Letters Patent.

Patented July 23, 1907.

Application filed June 3, 1907. Serial No. 376,980.

To all whom it may concern:

Be it known that I, FRANK L. THOMPSON, a citizen of the United States, residing at Wheatland, in the county of Oklahoma and Territory of Oklahoma, have 5 invented certain new and useful Improvements in Tail-Blocks for Sulky-Plows, of which the following is a specification.

My invention relates to plows, more especially that class known as sulky or riding plows which have a 10 rear swivel or caster-wheel with its standard pivotally secured in a tail-block bolted to the beam of the plow and projecting rearwardly, which will, hereinafter be more fully explained.

The objects of my invention are; first, to provide a 15 tail-block for sulky plows by the means of which a boy large enough to drive a team but not large enough to work a lever or a pedal can plow and turn corners without difficulty; second, to simplify the tail-block by dispensing with some of its parts and attachments; 20 third, to dispense with the necessity of working pedals or levers in turning corners; fourth to provide means whereby the driver may turn the wrong way without damage to the plow or its attachments. I attain these objects by the mechanism illustrated in the 25 accompanying drawings forming a part of this specification, in which—

Figure 1 is a right side elevation of a sulky plow showing my improved tail-block attached thereto, unnecessary parts omitted and parts of the plow being 30 broken away; Fig. 2 is a part sectional plan view; Fig. 3 is a part sectional plan view on line x Fig. 1; Fig. 4 is part plan view of the locking-cap; Fig. 5 is a part sectional elevation of the locking-cap and a portion of the tail-block; Fig. 6 is a right side elevation 35 of the latch as attached to the tail-block; Fig. 7 is a rear elevation of the tail-block and locking-cap.

Similar letters refer to similar parts in the several views.

Referring to the drawings, A is the beam of an ordinary sulky plow of the right hand style, B is the land-side and C is the moldboard of the plow, a portion of which is broken away to show parts otherwise obscured, D refers to the bolts securing the plow beam to the land-side; a is the tail-block, preferably of malleable iron, firmly secured to the plow beam A by the bolts E; the front edge of said block is thin and even with the edge of the plow beam and increases in thickness from the edge back a short distance, the portion which contacts with the plow beam conforms to the 40 contour of the side of the beam to aid in securing rigidity to the said block, which has a slight off-set at the rear edge of the beam A, from which it extends rearward on a line therewith, terminating in a cylindrical swell b having a vertical opening therethrough 45 for the reception of the standard or pivotal portion F' of the shaft F having its rear end bent at a right angle

forming the axle F'' for the wheel G; to maintain the said shaft in position the pivotal portion F' has the cap or collar c firmly secured thereon by means of set-screws d, the said cap contacting with the upper portion of the swelled or tubular portion b of the tail-block a; c' is a horizontal flange projection of the cap c, which may properly be called a check or a stop, its office being to prevent the said wheel from turning the wrong way while operating in conjunction with the 60 latching-bar e having a shoulder e' normally contacting with the front edge c'' of the said flange or stop c'; the opposite or front end of the said latching-bar is pivoted in a slot or groove at the upper edge of the 65 said tail-block formed by vertically projecting ears f f being a part of said block, the bolt g serving as the pivot; from the outer vertical side of the said latching-bar projects the foot-lug e'' having its upper surface at a right angle to the said latching-bar e, and from the under edge of the said bar a stud e''' projects 70 which is encompassed by the upper end of the spiral spring h having its lower end resting upon the strengthening-rib a' the purpose being to maintain the free end of the latching-block against the under surface of the cap c; to relieve the bolt g from unnecessary strain 75 the pivotal end of the latching-bar e may be rounded and its seat adapted to it as shown in Fig. 6.

To provide for sulky plows of the tongueless variety, which require that their caster wheel be locked while going down declines during transportation from field 80 to field or on the road, the eye b' is cast upon the swell or tubular portion b of the tail-block a and on the side which the said wheel travels; the hook rod H has one of its ends formed into a hook adapted to engage the spokes of the said wheel the opposite end being formed 85 into an eye loosely engaging the eye b', see Fig. 1. To prevent the rod H from engaging the wheel G at undesirable times the hook i is provided upon the side of the tail-block a and during disuse the said rod H 90 may rest therein, as shown by the dotted lines in Fig. 1.

I have described a tail-block for a right-hand plow, but it is equally well adapted to a left-hand plow by reversing certain of its parts which are too apparent to require description, they are made rights and lefts to correspond with the plows to which they are adapted 95 and attached.

In operation, it will be understood that a right-hand plow in the act of turning corners turns to the left; therefore, by referring to Fig. 2 it will be seen that the plow is free to turn to the left at a right-angle, 100 or even more, as indicated by the dotted lines, but cannot turn to the right, except that the driver press the latching-bar e downward until its shoulder e' passes below the contact or butting point c'' of the check-flange c' of the collar c which is firmly but adjustably secured upon the pivotal standard F'. The 105 latching-block e may be pressed down by the butt of

a whip or by the driver placing his foot upon the pedal-lug e'' and pressing downward; the said block will assume its normal position when the plow and its caster wheel assume a direct line.

5 Having thus described my invention, what I claim as new and desire to secure by Letters Patent, is—

1. In combination with a sulky plow, a tail-block a having a body portion adapted to be bolted to the beam of the plow and having a vertical web portion extending rearward 10 terminating in a swell or tube b with an eye b' upon its side to support a locking-hook and having vertical ears f perforated for a bolt and having an upwardly turned hook i upon the face side of said tail-block to support the said locking-hook, the locking-bar e having its forward end 15 pivotally secured between said ears by means of said bolt the said latching-bar having a shoulder e' upon its rear end and projecting from its face side a foot or pedal-lug by which to depress the said bar, substantially as described.
2. In combination with sulky plows having caster 20 wheels, a tail-block to support a castor wheel and having a body portion firmly secured to the plow beam, an upwardly turned hook i projecting from its face side, a pair of

vertical ears extending from its upper edge which have perforations in which a bolt is secured, a latching-bar having one of its ends pivoted upon said bolt its opposite end 25 being shouldered and having a pedal-lug projecting from its face side, spring tension being provided for maintaining the said latching-block in its normal position, the flanged collar or cap c provided with set-screws for adjustably and firmly securing the same upon the standard portion of the castor wheel shaft pivotally secured in the rear tubular portion of the said tail-block which maintains said wheel upright, the check-flange c' extending horizontally from the collar or cap c and having a butting edge c'' to contact with the shoulder or end of the said 30 latching-bar to prevent the plow from turning the wrong way, substantially as described and for the purposes set forth.

In testimony whereof I affix my signature in presence of two witnesses.

FRANK L. THOMPSON.
